METHOD OF TEMPERING CONTINUOUSLY
ANNEALED METAL SHEET

Albert Joseph Klein, Arlington Heights, Ill., assignor to
American Can Company, New York, N.Y., a corpora-
tion of New Jersey

Filed Oct. 4, 1963, Ser. No. 314,842
6 Claims. (Cl. 148—12)

This is a continuation-in-part of my co-pending ap-
plication, Serial No. 235,950, filed November 11, 1962,
now abandoned.

This invention relates to the method of manufacturing
ferrous metal sheet. More particularly it refers to a
method of producing ferrous metal sheet having high stiff-
ness and resistance to bulging.

Prior to this invention, difficulty has sometimes been
encountered with sheet metal containers that are used in
packaging products which are under substantial pres-
sure, such as carbonated beverages and beer. One of
the principal difficulties has been the inability of the
metals from which these containers are made to with-
stand the internal pressures produced by the products con-
tained therein, thereby causing the container to bulge
and even rupture the container seams in some cases.

Since the thickness of the material used in the manu-
facture of such containers is limited due to economic and
other factors, the approach followed in solving this prob-
lem has been to increase the strength of the materials
used in the manufacture of the containers without in-
creasing the material thickness. An early attempt at this
was made by Goss, U.S. Patent 2,165,368, who utilized
certain rolling and heat treating procedures in order to
produce a ferrous sheet metal having increased stiffness
and workability. However, his method left much to be
desired, since the strength of the metal sheet produced was
considerably lower than that necessary in the manufac-
ture of metal containers today.

Since the yield point in metals is where metals begin to
deform plastically, it is necessary to have as high a yield
point as possible in order to prevent metal from taking
a permanent "set" when some deformation occurs. By
means of Goss's technique, it is possible to produce sheet
steel having a yield strength of 55,500 p.s.i., the test being
run on strip having a thickness of 0.009 inch. This yield
strength is below that in use today, which is 62,000 to
64,000 p.s.i. As thinner strip is being planned for use
in container manufacture, it is apparent that even stronger
steel will be required, without substantially decreasing
the metals' formability.

It has been generally thought that increasing the degree
of cold reduction of metal strip will, in turn, propor-
tionally increase the stiffness of the metal. This concept
has been found to be not necessarily true. Previous to
this invention it has generally been held that the stiffness
of sheet metal depends only upon the magnitude of the
yield point; or, in other words, the higher the yield point,
the stiffer the metal with a corresponding decrease in
ductility. From this it would be reasoned that in order
to produce strip having appreciable stiffness, it would be
necessary to obtain a material having an extremely high
yield strength and therefore an extremely low ductility,
a ductility so low as to make the sheet difficult to work.

This invention has found that the biaxial stiffness in
continuously annealed, age-hardenable ferrous sheet metal
unexpectedly levels off substantially over an intermediate
range of temper rolling, while the yield strength expect-
edly increases gradually over the same range when the
metal is treated according to the teaching of this inven-
tion. Thus a metal having a modest yield strength, with
good formability, will have a biaxial stiffness substan-
tially equal to a more brittle less formable metal.

2

It is therefore an object of this invention to provide
a method of manufacturing metal sheet having appreci-
able stiffness, while maintaining its formability.

Another object is to provide a method of manufac-
turing ferrous metal sheet having superior resistance to
bulging without materially changing existing sheet metal
manufacturing procedures.

Still another object is to provide a method of the char-
acter described which can be readily and relatively inex-
pensively incorporated into present commercial proce-
dures for manufacturing metal sheet.

A further object is to provide a method of producing
thin ferrous metal sheet having superior stiffness without
excessively high yield strength.

Another object is to provide a new and improved metal-
lurgical process wherein stiffness properties of ferrous
sheet can be improved in a simple and effective manner,
without excessively cold working the metal strip.

Yet another object is to provide a method of producing
low-carbon steel sheet having strength and fabricability
substantially equal to conventionally manufactured con-
tinuously annealed sheet, although having a thickness
less than conventionally manufactured sheet.

A still further object is to provide low-carbon steel
sheet for manufacturing strong metal containers wherein
thinner sheet may be used, thereby reducing the quantity
of metal in the container, without substantially sacrific-
ing the required strength and formability.

Numerous other objects and advantages of the invention
will be apparent as it is better understood from the
following description, which, taken in connection with
the accompanying drawings, discloses a preferred em-
bodiment thereof.

In accomplishing the above objects, hot-rolled low
carbon steel strip is cold rolled until it is reduced in
thickness to 10 to 23% of its final gauge. The
strip is then continuously heat treated at a temperature
above 100° F., but below the A₁ point, thereby produc-
ing a spheroidized structure in the steel. Thereafter the
strip is further cold rolled to its final thickness. Subse-
quent to reaching the final gauge the strip preferably is
electroplated and the tin deposit is then flow brightened.

Referring to the drawings:

FIG. 1 is a schematic view showing the first cold roll-
ing operation followed by cleaning and the spheroidiza-
tion heat treatment.

FIG. 2 is a schematic view showing the cold reduction
of the strip to final gauge.

FIG. 3 is a schematic view showing the coating of
the strip.

FIG. 4 is a graph showing the relationship of stiffness,
dynamic ductility, and yield strength to the percent of
reduction in the final cold rolling operation.

As a preferred or exemplary embodiment, the instant
invention utilizes any low carbon steel, i.e., that having
a carbon content of 0.05 to 0.25%. This steel usually
contains other elements such as manganese, 0.40 to
0.80%, residual elements, and may also contain minor
amounts of alloying elements. This steel may be rimmed,
semi-killed or fully-killed steel.

A typical steel, that is used in the manufacture of con-
tainers for holding products under substantial pressure,
has the following nominal percentage chemical analysis:

Carbon	0.08—0.11
Manganese	0.50—0.60
Sulphur	0.02—0.03
Phosphorus	0.005—0.010
Silicon	0.005 max.
Molybdenum	0.004—0.006
Nickel	0.025—0.040
Chromium	0.018—0.023

Copper -----	0.009-0.013
Aluminum -----	0.010-0.016
Nitrogen -----	0.008-0.010
Iron -----	Balance

The steel, in the form of a strip 10, is cold reduced on a 4 to 6 stand four high tandem rolling mill, generally designated 12, from a hot rolled thickness of approximately 0.125 inch down to about 0.01 inch. In certain cases the cold rolled thickness may be reduced a lesser amount, e.g. to 0.025 inch, depending upon the final thickness desired.

The rolling mill is composed of a series of stands 14 having working rolls 16 and back-up rolls 18. Each of the stands 14 reduces the thickness of the strip 10 to a thickness less than the preceding stand.

Subsequent to the cold rolling operation the strip 10 is cleaned by a suitable commercial cleaning method such as illustrated by cleaning tank 20, containing a chemical cleaning composition 22. This removes any accumulation of oil or dirt deposited upon the strip 10 during cold rolling.

Upon leaving the cleaning operation, the strip 10 enters a continuous heat treating furnace 24 where the strip 10 is brought up to a temperature above 1000° F., but below the A_1 point (1333° F.). The heat-up time is about 20 seconds, followed by a hold time of about from 10 to 25 and preferably about 15 seconds.

During the hold time of this heat treatment two distinct changes take place in the steel.

Recrystallization of the steel occurs, substantially instantaneously, from a cold worked condition, i.e. elongated grains, to an annealed condition. With rimmed steel and semi-killed steel the grains in the annealed condition are substantially all equiaxed; whereas with fully-killed steel the grains in the annealed condition are a mixture of equiaxed and elliptical.

Also the shape of the carbides within the steel changes from slightly irregular to spheroidal. This change in carbide shape does not occur instantaneously, but requires a finite time interval, usually a matter of seconds.

It has been found that, for the purposes of the instant invention, the spheroidal shape of the carbides is essential and critical, but the shape of the steel grains is not.

However, it is possible to perform the heat treating step to obtain a spheroidal structure by heating slightly above the A_1 temperature for less than 5 seconds, then cooling slowly below A_1 , and holding until the desired structure is obtained.

Another method is to heat and cool the metal alternately between temperatures that are just above and below the A_1 temperature.

Complete recrystallization of the steel occurs almost instantly after the strip 10 reaches 1000° F. resulting in a fine grained material having an ASTM grain size of approximately 10 or greater. In order to minimize surface oxidation of the strip 10 it is generally desired that a non-oxidizing atmosphere, such as nitrogen, be used in the heat treating furnace 24.

To reduce the strip temperature to a value suitable for subsequent processing after leaving the heat treating furnace 24, the strip 10 enters a cooling chamber 26 where the strip 10 is cooled for about 15 seconds to a temperature of approximately 900° F. If the A_1 temperature is not exceeded during heat treatment to spheroidize the carbides, cooling may be effected more rapidly. Then the strip 10 enters another chamber 28, where the strip 10 is cooled as rapidly as possible to a temperature of approximately 250° F. This cooling usually requires about 50 seconds. It is desirable that both the cooling chambers 26 and 28 contain non-oxidizing atmosphere to prevent contamination of the metal surface. Once the strip has been cooled to approximately 250° F. it enters a third cooling chamber 30 where the temperature of the strip is brought down to ambient tempera-

ture. After heat treatment, the strip 10 is received on a coiler 32.

After the spheroidization heat treatment and cooling, the strip 10 is temper rolled to final gauge as shown in FIG. 2. A pair of four high tandem rolling mills 34 cold reduce the thickness of the strip 10% to 23%. It should be understood that the final temper rolling of the strip 10 may be done on rolling mills having either more or fewer stands without departing from the scope of this invention. Thus a single pass through a rolling mill giving a reduction of 10 to 23% will have the same desired stiffness and yield strength as will the strip that has been reduced a total of 10 to 23% through a plurality of rolling mills. It is preferred that a reduction of 10 to 18% be used for obtaining the most desirable properties, with a reduction from 10 to 14% optimum.

Once the strip 10 has been reduced to final gauge it may be used without further treatment in the fabrication of parts, or may be coated in order to increase its resistance to corrosion. If it is desired that an ordinary "tin can" be produced, the strip 10 is then coated by conventional electrotinning according to techniques well known in the art and illustrated in FIG. 3. Subsequent to electroplating, the tin is flow brightened by means also well known in the art, such as by using resistance or induction heating equipment 40 to produce a bright tinplate, which is commonly used in the manufacture of metal containers. Thereafter the strip is wound into a coil 42.

The instant invention is designed primarily for integration with the commercial production of tinplate; and for this reason it is preferred to temper roll the strip the designated 10 to 23% prior to the tinning operation. However, the desired increase in stiffness can also be obtained by temper rolling the strip to its final thickness after it has been tinned.

Yield strength of sheet steel when subjected to uniaxial tension, such as in a standard tensile test, does increase with the amount of cold working, e.g., thickness reduction by temper rolling, but does not change with the strip thickness, as does biaxial stiffness. Yield strength is shown in the curve in FIG. 4 wherein the yield strength of the low carbon steel strip increases from 55,000 p.s.i. at 3% reduction in thickness by temper rolling to 100,000 p.s.i. after a 50% reduction. Steel strip produced in accordance with the instant invention has an ultimate tensile strength of about from 70,000 to 85,000 p.s.i., a yield strength of about from 60,000 to 80,000 p.s.i. and a dynamic elongation of about 5 to 15%.

Completely unexpectedly it was found that sheet steel produced in accordance with the instant invention had a higher biaxial stiffness, i.e., resistance to bulging or deformation along two of its major axes, for a given thickness and degree of ductility, than steel rolled and heat treated according to conventional practice.

It has generally been accepted that biaxial stiffness is directly proportional to the yield strength of the steel. As can be seen in FIG. 4, the yield strength vs. percent reduction from temper rolling is nearly a linear relationship, resulting in an almost straight-line curve.

However, when the biaxial stiffness is plotted against the percent reduction from temper rolling, a slight peak is encountered at 18% reduction, with a leveling off, or plateau in the curve between 18 and 23% reduction and a sharp rise at about 25%. This was found for both strip rolled to 11 mils thickness and 7 mils thickness. It is apparent, though, that the biaxial stiffness will vary for a given rolling reduction for steel strip of different thicknesses.

Another factor that enters into the consideration of the degree of temper rolling to be done to produce the optimum strength with good formability in the strip is the dynamic ductility, as measured by percent elongation in a standard tensile test, except that the strain rate

was 0.5 foot per second rather than the standard 0.0003 foot per second. The dynamic ductility thus gives a close estimate of the forming properties of the metal during such operations as drawing, stamping, and punching.

It is evident in FIG. 4 that the dynamic ductility decreases sharply between 10 and 18%, while the yield strength increases gradually and biaxial stiffness increases gradually and tends to level off near 18%.

As indicated previously, the ductility of the sheet steel generally decreases as the yield strength increases. Contrary to the apparent teachings of the prior art, as was hereinbefore discussed, FIG. 4 shows that biaxial stiffness does not continue to increase with yield strength. Therefore, by means of the instant invention, for any given sheet thickness, high biaxial stiffness is obtained without greatly increasing the yield strength of the sheet and thereby substantially lowering its ductility; or in other words ductility is maintained at an operable level while obtaining high biaxial stiffness.

It is thought that the invention and many of its attendant advantages will be understood from the foregoing description and it will be apparent from the foregoing description that changes may be made in the steps of the method described and their order of accomplishment without departing from the spirit and scope of the invention or sacrificing all of its material advantages, the form hereinbefore described being merely a preferred embodiment thereof.

I claim:

1. In a method of producing low carbon ferrous sheet metal strip having high stiffness and yield strength with satisfactory formability, whereby said strip is hot rolled to an intermediate thickness, then cold reduced at least 80%, the steps comprising: continuously heat treating said cold reduced ferrous strip at a temperature above 1000° F. and below 1400° F. for a time of about from 10 to 25 seconds, whereby the carbides in said ferrous

5 strip assume a spheroidal structure; cooling said heated strip to substantially ambient temperature; and temper rolling the cooled strip to a thickness whereby a reduction of from 10 to 23% is made in the thickness of the

10 strip, thus producing a strip having increased stiffness and adequate formability.

2. The method of claim 1 wherein said cold rolled strip is heated between 1000° F. and the A_1 temperature.

3. The method of claim 1 wherein said cold rolled strip is heated above the A_1 temperature for less than 5 seconds and then cooled slowly to a temperature slightly below the A_1 temperature and held at said temperature below the A_1 temperature until a spheroidized structure is obtained in the ferrous metal.

15 4. The method of claim 1 wherein said cold rolled strip is alternately heated and cooled between temperatures slightly above and slightly below the A_1 temperature until a spheroidized structure is obtained in the ferrous metal.

5. The method of claim 1 wherein the heat treated strip is temper rolled to a thickness reduction of from 10 to 18%.

20 6. The method of claim 1 wherein said temper rolled strip is electrolytically coated with tin.
